UNITED STATES PATENT OFFICE.

WILLIAM H. RAMM, OF SEATTLE, WASHINGTON.

SUBMARINE-BOAT ATTACHMENT.

1,182,208.

Specification of Letters Patent.

Patented May 9, 1916.

Application filed September 22, 1914. Serial No. 863,000.

To all whom it may concern:

Be it known that I, WILLIAM H. RAMM, a citizen of the United States, residing at Seattle, in the county of King and State of Washington, have invented certain new and useful Improvements in Submarine-Boat Attachments, of which the following is a specification.

My invention relates to new and useful improvements in a submarine boat attachment and more particularly to an indicator for locating the position of a sunken submarine boat.

The primary object of the invention is the provision of such an attachment which will not retard the operation of the boat and which may be easily released at the desired moment.

A further object of the invention is the provision of means for severing the connecting means whereby the attachment is released from the boat.

A still further object is the provision of means for connecting the cable to the submarine boat after the indicator has been released.

With these and other objects in view the invention consists in the novel details of construction and arrangement of parts which will be more clearly understood from the following description and drawings, in which:

Figure 1 is a perspective view showing the sunken boat with the indicators released and upon the surface of the water. Fig. 2 is a transverse vertical section through the boat and indicator attached thereto. Fig. 3 is a longitudinal vertical section on the line 3—3 of Fig. 2. Fig. 4 is a detail in plan of the supporting drum. Fig. 5 is a longitudinal sectional detail of the cable drum and casing therefor. Fig. 6 is a fragmental detail of the cable severing knives. Fig. 7 is a top plan of the indicator. Fig. 8 is a sectional view of the top of the supporting drum housing. Fig. 9 is a vertical section through the cable-connecting block. Fig. 10 is a transverse sectional view through the cable-connecting block. Fig. 11 is a vertical sectional detail of one of the releasing slides for the cable-connecting block, and Fig. 12

is a side elevation showing in detail the cable connector.

In describing my invention I will separate the several details into three sections, 55 namely, the fastening mechanism for holding the indicator floats to the submarine boat, the severing mechanism for releasing the indicators or floats from the boat, and the cable-connecting mechanism for connecting the ends of the cable for supporting the boat from the indicators or floats. 60

In Fig. 1 of the drawings I have shown a perspective view of a sunken submarine boat supported from the indicator floats and 65 have indicated the submarine boat generally by A and the indicator floats by B.

Fastening mechanism.—Within the submarine boat A are provided two casings 1 which are supported upon the brackets 2 70 and within these casings 1 are mounted the rotatable drums 3 upon which are wound the cables 4. Secured upon the top of the submarine boat is a casting 5 having the groove 6 formed in the top thereof, as more 75 clearly shown in Fig. 8 of the drawings, and within the groove is adapted to be received a rubber packing. A drum 7 is mounted within the casting and the purpose and operation thereof will be later described. 80 Surrounding the casting 5 is a casing 8 and the indicating float B is adapted to rest upon the casting and is provided on the bottom with the tongue 9 which is adapted to be received within the groove 85 6 and upon the rubber packing. Connected to the casings 1 are the pipes 10 which extend from the casings to the top of the boat and are connected to a plate, as indicated at 11. The cables 4 are adapted to pass 90 through the pipes 10 and through the top of the boat and are connected to an eye 12 which is secured to the underside of the indicator float B. Tubes 13 extend vertically 95 through the indicator float, as more clearly shown in Fig. 3 of the drawings, and passing through these tubes 13 are the rods 14 having the ends threaded to receive the nuts 15 and between the nuts and the top of the float are the washers 16 which prevent water 100 from entering the tubes 13. Extending from the top of the casing 8 and into the

top of the submarine boat are the pipes 17 which are in alinement with the tubes 13 and connecting the ends of the pipes 17 on the interior of the boat are the pipes 18 and 5 casting 19. The rods 14 are provided on the lower ends with eyes and connected to the eyes and passing through the pipes 17, the connecting pipes 18 and casting 19 is a cable 20. This cable 20 acts as the connecting 10 means for holding the indicator float to the submarine boat. It will be understood that when this cable 20 is severed the indicator float will rise, drawing the cables 4 through the pipes 10 and from the drums 3.

15 *Severing mechanism.*—The severing mechanism is more clearly shown in Figs. 2, 3 and 5 of the drawings, and comprises a cylinder 21 connected to the casting 19 having a pipe 22 entering the bottom thereof and said 20 pipe 22 is connected to any source of compressed air supply. A piston 23 operates within the cylinder and is provided with the upwardly extending rod 24 which has the sharpened end 25 and a coil spring 26 surrounds the rod between the piston head and the bottom of the casting. The casting is provided with a central opening through which the rod 24 passes and is also provided with a shoulder upon which is secured a 30 blade 27 which acts with the pointed end of the rod 24 for severing the cable 20. It will be understood that when it is desired to sever the cable to release the indicator float air is admitted to the bottom of the cylinder which 35 forces the piston upwardly and thereby severs the cable between the pointed end of the rod 25 and the blade 27.

40 *Cable-connecting mechanism.*—On the ends of the cables 4 which are connected to the indicator floats B and wound upon the drums 3 are secured the balls or enlargements 28, as more clearly shown in Fig. 9 of the drawings. It is necessary when the indicator float is released from the boat and 45 the boat sinks to have some means for connecting the two free ends of the cables 4, whereby they will support the boat and connect the float thereto. For this purpose I have provided the blocks 29 which are 50 supported upon the top of the boat and are provided with central openings 30 which are adapted to register with the openings of the pipes 10 which extend through the top of the boat. These blocks 29 55 are supported upon the top of the boat by means of sliding bolts 31 which pass through angle iron brackets 32 secured to the boat and enter depressions or sockets 33 formed in the blocks 29, as more particularly shown in Fig. 10 of the drawings. Sockets 34 are formed in the blocks 29 adjacent the central opening 30 and within 60 the sockets are received the sliding blocks 35 having the extensions or stems 36 which

pass through openings 37 in the blocks and 65 engage the ends of the sliding bolts 31. The blocks 35 have pins 38 extending at an angle therethrough and are adapted to be engaged by a spring-held catch 39 which normally holds the ends of the pins 38 below 70 the bottom surface of the blocks. The pins 38 are provided with offsets or lugs 49, which normally rest on the shoulder 50 of the blocks 35. The blocks 29 are provided with sockets 40 to receive the enlarged heads 75 41 of pins 42 which pass through openings in the blocks and are adapted to engage in openings in the sliding blocks 35 and rest upon the top of the pins 38. Plugs 43 are received in the ends of the openings 40 and 80 between the enlarged heads 41 and plugs 43 are held springs 44. Lugs 45 are formed on the blocks 29 and connected to the lugs 45 of the two adjacent blocks is a cable 46.

85 When the indicator float is released and the cable drawn from the drum the enlarged heads 28 on the ends of the cables will be drawn through the pipes 10 until they engage the pins 38 carried by the sliding blocks 35. The lugs 49 will force the pins 39 backward 90 until the lugs are above them, when the pins will return to their normal position thereby holding the pins 38 in a raised position. The pins thus raised will release the pins 42 from the sliding blocks and the 95 blocks will then be forced back into the sockets 34 and the stems on the sliding blocks will disengage the sliding bolts 31 from the sockets formed in the blocks 29. The blocks thus being released from the boat 100 will be allowed to rise and the cable 46 will engage and surround the underside of the drums 7. It will thus be seen that the ends of the cables are connected and by engaging the underside of the drum will support the 105 boat.

110 The indicator float may be made of any desired shape but preferably that shown in Figs. 3 and 7 of the drawings, and is provided with a plurality of windows 47 and the removable plate 48 by means of which a person may enter the float. The indicator float may carry a signal light, a sounding signal and telephone and wireless telegraphy connections.

115 Having fully described the detailed construction of the device it is thought that the operation and advantages will be clearly understood.

120 While in describing the invention I have merely described the construction and operation of one indicator float and connecting and severing mechanism it will be understood that two or more of these indicator floats are carried by each boat. Preferably 125 there will be two floats, one fore and one aft of the boat. Should the boat sink or become disabled in any manner so that it is

not able to rise to the surface of the water it is only necessary for the operator to admit air into the cylinder 21 which operates the piston and severs the cable, thereby disconnecting the float from the boat. The float will then rise to the surface unwinding the cables from the drums until the enlarged heads on the cables disengage the blocks which carry the connecting cable. The 10 connecting cable engaging the drum 7 will support the boat from the floats which are of sufficient buoyancy to support the boat. In order that the cables cannot be twisted by the floats turning, I have provided means 15 for connecting the floats, said means, as shown in Fig. 1 of the drawings, merely consisting of a cable connected to the ends of the floats. However, I do not wish to limit myself to this particular form of connecting 20 means as any means might be used. The floats may be either released from the boat while the boat is sinking or may not be released until the boat has settled to its greatest depth. If the floats are not released until the boat is settled they would have to be of sufficient buoyancy to withstand the pressure of the water at such a 25 depth and rise to the surface.

The floats being on the surface of the 30 water will indicate to other boats that the boat is sunken and allow them to raise the same. In raising a boat of this character it will ordinarily be found that the cables connected around the drums will not be of sufficient strength to raise the boat but this can be easily overcome by merely securing any 35 heavier cable to one end of the supporting cable and by drawing the opposite end the larger or heavier cable is drawn around the supporting drum and may then be attached 40 to any form of hoisting mechanism for raising the boat.

Having fully described the invention what 45 I claim as new and desire to secure by Letters Patent is:—

1. A boat indicator comprising a float, means for connecting the float to the boat, and means for severing the connecting means.
2. A boat indicator comprising a float, means connecting the float to the boat, means for severing the connecting means, and means connected to the float for supporting the boat.
3. A boat indicator comprising a float, a cable for connecting the float to the boat, means for severing the cable, a supporting drum carried by the boat, and means connected to the float and adapted to engage the supporting drum for supporting the boat.
4. A boat indicator comprising a float, a cable for connecting the float to the boat, means for severing the cable, drums carried

by the boat, and cables connected to the 65 float and drums for allowing the float to rise when disconnected from the boat.

5. A boat indicator comprising a float, a cable for securing the float to the boat, means for severing the cable, a casting secured to the boat, a supporting drum mounted in the casting, and means connected to the float and adapted to engage the supporting drum for supporting the boat.

6. A boat indicator comprising a float, 75 rods passing through the float, a tube secured to the boat, and a cable secured to the rods and passing through the tube for connecting the float to the boat.

7. A boat indicator comprising a float, 80 rods passing through the float, a tube secured to the boat, a cable secured to the rods and passing through the tube, and means connected to the tube for severing the cable.

8. A boat indicator comprising a float, 85 casting secured to the boat, a drum mounted in the casting, a tube secured to the boat, a cable passing through the tube and connected to the float, means for severing the cable, and means carried by the float and 90 adapted to engage the drum in the casting for supporting the boat.

9. A boat indicator comprising a float having a projection on the bottom thereof, a casting secured to the boat and having a 95 groove in the top thereof to receive the projection on the float, means for connecting the float to the boat and means for severing the connecting means.

10. A boat indicator comprising a float, 100 means for connecting the float to the boat, a casting secured to the boat, and a severing device carried by the casting for severing the connecting means.

11. A boat indicator comprising a float, a 105 casting secured to the boat, tubes connected to the casting, a cable secured to the float and passing through the tubes and casting, a cylinder secured to the casting, a piston operating in the cylinder, and means carried 110 by the piston and operating in the casting for severing the cable.

12. A boat indicator comprising a float, drums mounted in the boat, casings surrounding the drums, pipes connected to the 115 casings and passing through the boat, and cables connected to the float and passing through the pipes and received on the drums.

13. A boat indicator comprising a float, drums mounted in the boat, cables secured 120 to the float and adapted to be wound upon the drums, enlargements formed on the ends of the cables, and means for connecting the enlarged ends.

14. A boat indicator comprising a float, 125 cables carried by the float and having enlarged ends, castings mounted upon the boat, and means for releasing the castings

when engaged by the enlarged ends of the cables.

15. A boat indicator comprising a float, cables having enlarged ends secured to the float, castings mounted upon the boat, means for releasing the castings when engaged by the enlarged ends of the cables, and means connecting the castings.

16. A boat indicator comprising a float, cables having enlarged ends secured to the float, castings mounted upon the boat, sliding bolts connected to the boat and adapted to engage the castings, and means for releasing the bolts when engaged by the enlarged ends of the cables.

17. A boat indicator comprising a float, cables secured to the float and having enlarged ends, a casting secured to the boat, a drum mounted in the casting, blocks having central passages through which the cables pass, catches adapted to engage the blocks, means for releasing the catches, and means connecting the blocks and adapted to engage the drum on the boat.

25 18. A boat indicator comprising a float, means for connecting the float to the boat, means for severing the connecting means, blocks carried by the boat, cables connected to the float and blocks, means connecting the blocks, and means attached to the boat and adapted to engage with the block connecting means.

19. A boat indicator comprising a float, cables connected to the float, blocks having central openings through which the cables pass, sockets formed in the blocks, blocks slidably in said sockets, catches mounted on the boat and adapted to engage the first mentioned blocks, and means connected to the sliding blocks in the sockets for disengaging the catches and releasing the blocks.

20. A boat indicator comprising a float, cables connected to the float, blocks carried by the boat and having central openings to receive the cables, sliding catches operating in the blocks, pins for locking the catches, and means for releasing the pins.

25 21. A boat indicator comprising a float, cables secured to the float, blocks having central openings through which the cables pass, sliding bolts carried by the boat and adapted to engage the blocks, sliding blocks mounted in the blocks and having pins extending therethrough, spring-held catches engaging the sliding blocks and pins, releasing bolts connected to the sliding blocks for releasing the sliding bolts, and means connected to the cables and adapted to engage the pins for releasing the blocks.

22. A boat indicator comprising a float having openings therethrough, a tube carried by the boat and the ends in alinement with the openings in the float, rods passing through the openings in the float, a cable

secured to the rods, and means for severing the cable.

23. A boat indicator comprising a float, blocks carried by the boat, a drum secured to the boat, cables secured to the float and blocks, and means connecting the blocks and adapted to engage the drum.

24. A boat indicator comprising a float, means for connecting the float to the boat, means for severing the connecting means, a drum carried by the boat, blocks mounted on the boat, cables connected to the float and blocks, and means connecting the blocks for engaging the drum.

25. A boat indicator comprising a float, means for connecting the float to the boat, means for severing the connecting means, drums carried in the boat, casings surrounding the drums, tubes leading from the casings to the top of the boat, cables connected to the float and passing through the tubes, blocks connected to the boat over the ends of the tubes, and means carried by the cables for releasing the blocks.

26. A boat indicator comprising a float, means for connecting the float to the boat, means for severing the connecting means, a casting secured to the boat, a drum mounted in the casting, drums mounted in the boat, casings surrounding the drums, tubes connected to the casings and extending to the top of the boat, cables secured to the float and passing through the tubes, blocks mounted on the boat over the ends of the tubes, means carried by the cables for releasing the blocks, and means connecting the blocks and adapted to engage the drum mounted in the casting.

27. A boat indicator comprising a float, a tube secured to the boat, a cable secured to the float and passing through the tube, a sliding knife connected to the tube for severing the cable, a casting secured to the boat, a drum mounted in the casting, drums mounted in the boat, casings surrounding the drums, tubes leading from the casings to the top of the boat, cables secured to the float and passing through the tubes to the drums, enlargements secured on the ends of the cables, blocks mounted upon the boat, means carried by the blocks and adapted to be engaged by the enlarged ends of the cables for releasing the blocks, and means connecting the blocks and adapted to engage the drum in the casting.

28. A boat indicator comprising a float, cables secured to the float, blocks having central openings through which the cables pass, sliding bolts carried by the boat and adapted to engage the blocks, sliding blocks mounted in the blocks, pins extending through the sliding blocks, lugs formed on said pins, catches engaging the sliding blocks and pins, releasing bolts connected to the sliding blocks for releasing the sliding blocks.

bolts, and means connected to the cables and adapted to engage the pins for releasing the blocks.

29. A boat indicator comprising a float, tubes passing through the float, rods positioned within the tubes, a tube secured to the boat and alining with those in the float, a cable secured to the rods and passing

through said last mentioned tube, and means for severing the cable. ¹⁰

In testimony whereof I affix my signature in presence of two witnesses.
